Inventor,

Algermont H. Waldo

By Nissen & Crane

Atlys.

UNITED STATES PATENT OFFICE.

ALGERMONT H. WALDO, OF ST. PAUL, MINNESOTA, ASSIGNOR TO CREX CARPET COMPANY, OF NEW YORK, N. Y., A CORPORATION OF DELAWARE.

DESIGN FOR A RUG.

57,550.

Specification for Design.

Patented Apr. 12, 1921.

Application filed January 3, 1921. Serial No. 434,789. Term of patent 3½ years.

To all whom it may concern:

Be it known that I, ALGERMONT H. WALDO, a citizen of the United States, residing at St. Paul, in the county of Ramsey and State of Minnesota, have invented a new, original, and ornamental Design for a Rug, of which the following is a specification, reference being had to the accompanying drawing, forming a part thereof, and wherein the figure is a plan view of a rug showing my new design.

I claim:

The ornamental design for a rug, as shown.

Signed at St. Paul, Minnesota, December 29th, 1920.

ALGERMONT H. WALDO.
